FOUNTAIN

Henry K. Cowen, Milwaukee, Wis.

Application September 4, 1956, Serial No. 42,827

Term of patent 14 years

(Cl. D91—4)

Fig. 1 is a view in side elevation of a fountain showing my new design.

Fig. 2 is a detail view taken in section on the line 2—2 of Fig. 1 thereof.

I claim:

The ornamental design for a fountain, as shown.
